H. W. MATALENE,
STEM WINDING AND SETTING WATCH,
APPLICATION FILED DEC. 30, 1908.

918,759.

Patented Apr. 20, 1909.

UNITED STATES PATENT OFFICE.

HENRY W. MATALENE, OF BOSTON, MASSACHUSETTS.

STEM WINDING AND SETTING WATCH.

No. 918,759.

Specification of Letters Patent.

Patented April 20, 1909.

Application filed December 30, 1908. Serial No. 469,924.

To all whom it may concern:

Be it known that I, HENRY W. MATALENE, a citizen of the United States, and a resident of Boston, in the county of Suffolk and State of Massachusetts, have invented certain new and useful Improvements in Stem Winding and Setting Watches, of which the following is a specification.

This invention relates to watches in which both the winding and setting operations are performed through the agency of the winding stem, and resides in certain features of construction and arrangement hereinafter described and claimed.

In the accompanying drawings: Figure 1 is a front elevation, partly in section, of a watch embodying my invention; Fig. 2 is a rear elevation of the upper portion of the watch with a part of the back broken away; and Fig. 3 is a vertical section on the line $x-x$ in Fig. 2.

The watch illustrated in the drawings comprises a center 2, a bezel 3, a crystal 4, a cap 5 and a hinged back 6, which parts may be of the usual or any suitable construction except in so far as the configuration of certain of these parts may need to be modified in order to receive and coöperate with the mechanism hereinafter described.

The case formed by the parts above described is adapted to receive a watch movement which may be of any desired construction, so long as it is provided with a winding stem which may be rotated to wind the watch when in its normal position and may also be moved longitudinally into setting position and then rotated to set the watch. A portion of such a winding stem is shown at 7, and the upper end of said stem 7 is provided with a cylindrical terminal portion or winding terminal 8 which is located in a recess 9 in the center 2 of the watch case and forms, in effect, a part of the winding stem. Said winding terminal 8 is provided with two circumferential grooves 10 and 11, each preferably bounded on its upper side by an inclined surface and on its lower side by a horizontal ledge, and a catch 12 having a beveled upper face is arranged to move horizontally toward and away from the winding terminal 8 at one side of the latter, being normally pressed forward by means of a spring 13 to which it is attached and which is secured at one end to the center 2 of the watch case, as shown in Fig. 2.

A vertical notch 14 of sufficient width to

receive the catch 12 connects the annular grooves 10 and 11, and the upper end of the winding terminal 8 is provided with means whereby it and the winding stem may be rotated as well as moved longitudinally inward and outward as hereinafter described. In the particular construction illustrated, provision is made for imparting these movements to the winding terminal by means of an eye 15 secured thereto and a link 16 passing through said eye, which eye and link serve as a means for suspending the watch from a neck chain or a chatelaine pin, this arrangement being particularly designed and adapted for use in locket watches as set forth in a prior application for U. S. Letters Patent filed by me on the 25th day of June, 1908, Serial No. 440,217, in which a locket watch construction of this sort is described and claimed. This particular arrangement for suspending the watch is not an essential part of my present invention, however, and may be replaced by any other suitable means for imparting the desired movements to the winding terminal and stem, whether the watch is suspended from said terminal or not. As thus constructed, when the winding terminal 8 and stem 7 are in their normal or winding position, which is that shown in Fig. 3, the catch 12 overlies the horizontal ledge at the bottom of the upper annular groove 10 and thus prevents outward movement of the winding terminal and stem unless the same are rotated into such position as to bring the vertical notch 14 directly beneath the catch, but after this has been done the winding terminal and stem may be pulled outward until such movement is arrested by the engagement of the catch 12 with the horizontal ledge at the bottom of the lower groove 11, whereupon the parts will be in position to set the watch by rotating the terminal 8. After the watch has been set the winding stem may be pushed directly inward into winding position, by which movement the catch 12 will be pushed outward by the action of the inclined face above the lower groove 11, and as soon as the upper horizontal ledge passes beneath the catch the latter will be thrown into the position shown in Fig. 3 by means of its spring 13, which may be conveniently arranged to play in a space provided for the purpose between the inner edge of the back 6 and the outer edge of the cap 5 at the upper portion of the watch case.

In case the outer end of the winding ter-

5 minal 8 is provided with an eye 15 for suspending the watch, as shown, or with equivalent suspending means, the plane occupied by this eye should be so related to the location of the notch 14 that the normal position assumed by the watch when suspended will be one in which the catch 12 is out of register with said notch 14, so as to prevent an accidental or premature outward movement of the terminal 8 from being brought about by the weight of the watch, or by a pull upon it.

10 While my present improvements are applicable to stem winding and setting watches 15 in general, they are particularly adapted and intended for use in locket watches which are suspended directly from the outer end of the winding stem, as set forth in my prior application above referred to, and have the 20 advantage, as compared with the particular construction shown and described in said prior application, that the necessity for opening the watch case in order to set the watch is avoided.

25 I claim as my invention:—

1. A stem winding and setting watch comprising a winding stem having at its outer end a terminal portion mounted to rotate and to move longitudinally in the case 30 of the watch, said parts being provided respectively with two annular grooves connected by a notch and with a movable catch arranged to enter one or the other of said grooves, according to the longitudinal position of the winding stem, and adapted to pass through said notch from one groove to the other.

2. A stem winding and setting watch comprising a winding stem having at its 40 outer end a terminal portion mounted to rotate and to move longitudinally in the case of the watch, said terminal portion being provided with two annular grooves located one above the other and having horizontal 45 lower walls to form stop faces, a spring-actu-

ated catch carried by the watch case and adapted to enter one or the other of said grooves, according to the longitudinal position of the winding stem, and having a stop surface on its under side to coöperate with 50 the stop surfaces of the respective grooves, and means carried by the outer end of said terminal portion for suspending the watch.

3. A stem winding and setting watch comprising a winding stem having at its 55 outer end a terminal portion mounted to rotate and to move longitudinally in the case of the watch, said terminal portion being provided with two annular grooves located one above the other and connected by a 60 vertical notch, and a spring-actuated catch arranged to enter one or the other of said grooves, according to the longitudinal position of the winding stem, and adapted to pass through said notch from one groove to 65 the other.

4. A stem winding and setting watch comprising a winding stem having at its outer end a terminal portion mounted to rotate and to move longitudinally in the case 70 of the watch, said parts being provided respectively with two annular grooves located one above the other and connected by a vertical notch and with a spring-actuated catch arranged to enter one or the other of 75 said grooves, according to the position of the winding stem, and adapted to pass through said notch from one groove to the other, and means for suspending the watch carried by the outer end of said terminal portion 80 and so arranged that said catch and notch are normally out of register with each other when the watch is suspended.

In testimony whereof, I have hereunto subscribed my name this 23rd day of December, 1908.

HENRY W. MATALENE.
